United States Patent Office

Des. 175,766
Patented Oct. 11, 1955

175,766

DIELECTRIC TEST SET

William P. Foster, Lansdowne, Pa., assignor to James G. Biddle Company, Philadelphia, Pa., a corporation of Pennsylvania

Application November 8, 1954, Serial No. 33,025

Term of patent 14 years

(Cl. D26—5)

FIG. 1.

FIG. 3.

FIG. 2.

FIG. 5.

FIG. 4.

Fig. 1 is a perspective view of a dielectric test set showing my new design;

Figs. 2 and 3 are front and side elevational views, respectively;

Fig. 4 is a front perspective view with the cover removed; and

Fig. 5 is a rear perspective view with the cover removed.

I claim:

The ornamental design for a dielectric test set, substantially as shown.
